United States Patent Office

Des. 203,407
Patented Jan. 4, 1966

203,407

DOOR HANDLE

Alois Crepinsek, San Jose, Calif., assignor to 777 Lock
and Engineering Corp., San Jose, Calif.

Filed May 19, 1965, Ser. No. 85,358

Term of patent 7 years

(Cl. D50—3)

FIG. 1

FIG.2

FIG.3

FIG.4

FIG. 1 is a perspective view of a door handle showing a new design;

FIG. 2 is a front view thereof;

FIG. 3 is a side view thereof;

FIG. 4 is a top view thereof.

The dominant features of my design reside in the solid line portion.

I claim:

The ornamental design for a door handle, as shown and described.
